ATTORNEY

UNITED STATES PATENT OFFICE.

JAMES A. FLOMERFELT, OF NEW YORK, N. Y.

DESIGN FOR A LINK CUFF-BUTTON.

SPECIFICATION forming part of Design No. 24,196, dated April 16, 1895.

Application filed March 7, 1895. Serial No. 540,899. Term of patent 14 years.

To all whom it may concern:

Be it known that I, JAMES A. FLOMERFELT, a citizen of the United States, residing at New York city, county and State of New York, 5 have invented a new and useful Design for Link Cuff-Buttons, of which the following is a specification.

Reference is to be had to the accompanying drawings, illustrating my design, in which—
10 Figure 1 is a side elevation of a link cuff-button embodying the design; and Fig. 2 is a front view thereof.

My design consists in the rearwardly curved or concaved intermediate shank portion 1 of 15 the button, as combined with, or viewed in

connection with, its angularly disposed heads 2, 3 at opposite ends of the shank, said heads leaning toward each other from the rear toward the front of the button, and as shown more particularly in Fig. 1 of the drawings. 20

What I claim is—

The design for a link cuff-button, substantially as herein shown and described.

In testimony whereof I affix my signature in the presence of two witnesses.

JAMES A. FLOMERFELT.
